Atty.

UNITED STATES PATENT OFFICE.

JAMES H. RAND, OF NORTH TONAWANDA, NEW YORK.

INDEX DEVICE.

1,227,663.

Specification of Letters Patent. Patented May 29, 1917.

Application filed July 18, 1916. Serial No. 109,975.

To all whom it may concern:

Be it known that I, JAMES H. RAND, a citizen of the United States, and resident of North Tonawanda, in the county of Niagara 5 and State of New York, have invented new and useful Improvements in Index Devices, of which the following is a specification.

This invention relates to indexes, and particularly to indexes of the so-called visible 10 index type in which a series of spaced cards are supported in a frame with the free edges of the cards projecting one beyond another.

In the accompanying drawings which illustrate certain embodiments of the invention,—

Figure 1 is a face view of part of an index containing the invention, certain parts being broken away; Fig. 2 is a face view of one of the cards with its supporting bar and 20 sheath;

Fig. 3 is a vertical cross section on an enlarged scale of the parts shown in Fig. 2;

Fig. 4 is a face view showing a modification;

Fig. 5 is a vertical cross-section on an enlarged scale of the parts shown in Fig. 4; and

Fig. 6 is a face view of a modification.

A represents the frame having inwardly 30 turned flanges *a* at its opposite edges forming inwardly facing guide channels. This frame may be of the usual construction.

A series of card supporting bars *b* are mounted in the frame with their ends held 35 in the guide channels. Said bars are preferably made of bristol board, leather board, or similar stiff resilient material of uniform thickness and smooth surface so that they will slide freely within the guide channels 40 of the frame. The cards, *c*, which may be of any suitable sheet material, such as cardboard or paper, whether comparatively thick or thin, may be attached to the supporting bars in any suitable way, as by 45 means of a hinge of textile fabric *d*, cemented to the back of the bar and the back of the upper margin of the card.

A protective sheath of transparent resilient material such as sheet celluloid, is 50 mounted on each supporting bar *b*, and extends substantially the length of the bar between the guide flanges *a* of the frame, terminating short of the guide flanges so as not to extend into the guide channels. This insures the free sliding of the bars *b* within the 55 guide channels, which would be interfered

with if the sheaths extended into the guide channels, since any inequality in the thickness of the sheaths or any tendency of the lips of the sheaths to spring open might 60 tend to bind the ends of the card supports in the channels and interfere with their free movement lengthwise thereof.

Each sheath has a closed front face *e* and inturned retaining lips *e*¹ and *e*² embracing 65 opposite edges of the bar *b*. The upper or outer lip *e*² is preferably folded again inwardly to form a rear face *e*³ behind the bar *b* and the fabric hinge *d*. The sheath may be removably secured to the supporting bar 70 *b* or it may be permanently fixed thereto, as by cementing the rear face *e*³ to the back of the bar. It is preferably mounted on the bar, however, without cementing so that the bar and card may be readily removed therefrom 75 and replaced by another bar and card when the latter is used up.

The index characters may be inscribed directly on the bar *b*, or, if preferred, a removable indicator strip *f* may be inserted in 80 the slideway formed between the front face of the bar and the front face of the sheath. As the sheath terminates short of the guide channels, said slideway has its entrance *e*⁴ outside of the guide channels so that the 85 indicator strip *f*, which is shown partly withdrawn in Fig. 4, may be inserted into and removed from the slideway without removing the bar from the index frame. With this construction it is possible to use 90 the card *c* and bar *b* merely as a holder for an insert or record slip, which may be held in a fold or pocket *g* at the free edge of the card, instead of writing the subject-matter of the index directly on the card 95 and bar. The insert and the index strip *f* may be removed and replaced as often as desired, while the card *c* and bar *b* may be used over and over again.

In the modification shown in Fig. 6, the bar *b* is omitted, and the ends of the sheath *e* itself are intended to be inserted in the guide channels *a* of the frame, the position of which is indicated by dotted lines. The sheath has a closed front face and inturned lips forming a slideway to receive and hold a removable indicator strip. An entrance opening *e*⁵ is formed in the front of the sheath at a point somewhat removed from the end of the sheath and outside of the 105 guide channels *a* so that an indicator strip *f* may be inserted or removed from the 110

sheath without removing the latter from the frame. The strip f' may be short, as shown, to serve for data which are frequently changing, while data of more permanent character may be placed on another strip f^2 ; or the strip f' could extend the whole length of the sheath. This modification secures the advantage of an entrance opening for the indicator strip clear 10 of the guide channels of the frame, as in the other forms, but does not insure the freedom of movement lengthwise of the guide channels which is secured by the bars b .

15 I claim:

1. An index comprising a frame having inwardly facing guide channels, a series of card supporting bars having their ends held within the guide channels and slidable 20 lengthwise thereof, cards supported in the frame by said bars, and a sheath of transparent resilient material on each supporting bar terminating short of the guide channels.

2. An index comprising a frame having inwardly facing guide channels, a series of card supporting bars having their ends held within the guide channels and slidable 30 lengthwise thereof, cards supported in the frame by said bars, a sheath of transparent resilient material on each supporting bar having a closed front face forming a slideway in front of the bar and terminating short of the guide channels, whereby the 35 entrance to the slideway is outside of the guide channels, and a removable indicator strip in said slideway.

3. An index comprising a frame having inwardly facing guide channels, a series

of card supporting bars having their ends 40 held within the guide channels and slidable lengthwise thereof, cards supported in the frame by said bars, and a sheath of transparent resilient material on each supporting bar having a closed front face and in- 45 turned retaining lips embracing the opposite edges of the bar, said sheath terminat- ing short of the guide channels.

4. An index comprising a frame having inwardly facing guide channels, a series 50 of card supporting bars having their ends held within the guide channels and slidable lengthwise thereof, cards supported in the frame by said bars, a sheath of transparent resilient material on each supporting bar 55 having a closed front face and inturned re- taining lips embracing the opposite edges of the bar, said sheath terminating short of the guide channels and said closed front face forming a slideway between it and 60 the bar whose entrance is outside of the guide channels, and a removable indicator strip in said slideway.

5. An index comprising a frame having inwardly facing guide channels, and a 65 series of sheaths of transparent resilient material supported in said frame between the guide channels, each sheath constitut- ing a slideway adapted to receive and hold a removable indicator strip and having an 70 entrance opening for such indicator strip located outside of the guide channels, whereby a strip may be inserted or re- moved without removing the sheath from the frame.

Signed by me at Boston, Massachusetts,
this 5th day of July, 1916.

JAMES H. RAND.
